The ornamental design for a diamond saw blade as shown and described.

DESCRIPTION

FIG. 1 is a front view of a diamond saw blade. The back view is a mirror image of the front.

FIG. 2 is a perspective view of the diamond saw blade.

FIG. 3 is a side view of the diamond saw blade; and, FIG. 4 is an enlarged view of the encircled portion of FIG. 3 labeled 4.

The dash-dash broken lines of FIGS. 3 and 4 depict the limits of the enlarged views and form no part of the claimed design. The dash-dash lead line in FIG. 3 labeled 4 indicates the area from which the enlargement in FIG. 4 is taken and forms no part of the claimed design.
